Attorney

UNITED STATES PATENT OFFICE.

WILLIAM R. TONKIN, OF BISBEE, ARIZONA.

DIRECTION SIGNAL.

1,418,036.

Specification of Letters Patent. Patented May 30, 1922.

Application filed December 7, 1921. Serial No. 520,651.

To all whom it may concern:

Be it known that I, WILLIAM R. TONKIN, a citizen of the United States, residing at Bisbee, in the county of Cochise and State 5 of Arizona, have invented certain new and useful Improvements in Direction Signals, of which the following is a specification, reference being had to the accompanying drawings.

10 This invention relates to direction signals for vehicles, and more particularly to improvements on direction signals disclosed in my Patent 1,339,589 of May 11, 1920.

It is an object of the invention to provide a signal of this character mounted for rotary movement, said signal being in the form of a lamp casing rotatable with respect to the lamp, and wherein the cover of the casing is provided with different 20 colored lenses which may be positioned upon rotation of the casing to indicate the direction of travel of the vehicle.

It is also an object of the invention to provide a signal of this character wherein 25 the lamp casing is rotatably mounted on the socket or support of the lamp, the casing being adapted to support signal lenses.

It is a further object of the invention to provide a device of this character, wherein 30 in the rear portion of the lamp casing is formed into a drum or pulley having a channel adapted to receive an operating cable, the cable being connected to the drum, so that upon actuation of the cable by the 35 driver, the casing will be rotated in the direction desired.

It is still a further object of the invention to provide a device of this character wherein the support on which the casing 40 is rotatably mounted also serves as a socket for the lamp casing, said socket being provided with means to prevent accidental disengagement of the socket from the lamp and for attachment to a suitable support.

45 With these and other objects in view, the invention consists in the improved construction and arrangement of parts to be herein-after more particularly described, fully claimed and illustrated in the accompanying drawings, in which:—

Figure 1 is a side elevation of a direction signal constructed in accordance with an embodiment of the invention;

Figure 2 is a front elevation; and

50 Figure 3 is a longitudinal sectional view through the signal and its support.

Referring to the drawings, 5 designates a bracket or support adapted to be secured to any portion of the vehicle, preferably the rear portion. The upper end of the bracket 60 is provided with a threaded opening 6. It is of course obvious that the bracket 5 may be disposed in any position desired to suit the convenience of the user, or in other words, to permit the bracket to be conveniently applied to the vehicle.

A tubular shaft and socket member 7 is provided, said shaft member being relatively long and having an annular flange 8 on one end, said flange extending outwardly in 70 angular relation to the exterior surface of the shaft and socket member. The exterior face of the opposite end 9 of the shaft 7 is threaded and adapted to engage the threads provided in the walls of the opening 6 whereby the shaft is secured to the bracket and permitted to project beyond one face thereof. A lock nut 10 is threaded on the projecting extremity of the end portion 9 and adapted to engage the bracket 5 to 80 lock the shaft and socket member to the bracket and hold the same rigid.

The signal proper consists of a casing 11 substantially frusto-conical in cross section. The forward edge 12 of the casing is 85 extended in angular relation to the body portion of the casing to form a rim, the purpose of which will be hereinafter described. The rear wall 13 of the casing is provided with a central opening adapted 90 to register with an opening provided in a partition 14 disposed inwardly of the casing in spaced parallel relation to the rear wall 13. A bearing sleeve 15 is disposed in the registering openings of the wall 13 95 and partition 14 and is adapted to receive the tubular shaft and socket member 7, the length of the bearing corresponding to the distance between the flange 8 and the adjacent face of the bracket 5. It will be 100 noted that the rear end 16 of the bearing member 15 projects beyond the rear wall of the casing, so as to prevent contact of the bracket 5 with the casing, and thereby eliminate friction to a large extent.

That portion of the outer wall of the casing disposed between the rear wall 13 and the partition 14 is provided with an upwardly projecting flange 17 adjacent the rear wall 13, said flange cooperating with 110 the adjacent portion of the casing to form an annular pulley channel 18 for the recep-

tion of an actuating cable 19, the cable extending around the pulley and having its ends connected to actuating means such as disclosed in my Patent 1,339,589, said means being disposed adjacent the driver's seat of the vehicle, so that movement of either portion of the cable will cause corresponding movement of the casing.

In connection with the casing, a novel form of lens or cover is used, said lens consisting of a plate 20. The edge 21 of the plate is extended in angular relation to the plate to provide a rim or collar adapted to engage the rim 12 of the casing, the rim 21 engaging the exterior face of the rim 12, suitable fastening means such as thumb screws 22 being used to secure the cover or plate 20 to the casing. Carried by the body portion of the plate 20 are lenses 23 and 24. The lens 23 is red and the lens 24 green. One-half of the plate 20 may be colored green and the other half red, corresponding to the green and red lenses, so that the plate may be readily discernible in the day time as well as night.

The tubular shaft member 7 also forms a socket for the reception of an electric lamp 25, said socket including contact means and also means for securing the lamp within the socket, the electric conductors 26 and 27 passing through the rear or end portion 9 of the socket member to a source of electric energy. By this means, the lamp is caused to remain stationary and yet at the same time project inwardly of the lamp casing so that the rays of the light may be projected to all portions of the casing. A novel feature of this casing is that the outer face of the partition 14 is made of highly polished or brilliant metal which serves as a reflector, for the lamp, in addition to providing a support for the bearing 15. By this means the light is reflected toward the lenses, the lens positioned uppermost or outermost indicating to following vehicles whether it is safe or dangerous to proceed further, the lenses being rotated into position by operation of the cable 19 disposed in the channel 18 of the lamp casing.

From the foregoing it will be readily seen that this invention provides a novel direction signal wherein the lamp casing performs a number of functions, namely, as a drum for the reception of the actuating

cable, as means for rotatably supporting the lamp casing, in addition to providing a support for the lenses of the lamp. Another important feature is that the exterior surface of the shaft 7 is used as a bearing for the rotatable lamp casing, while the interior surface of the shaft 7 is used as a socket for the lamp, the engagement of the lamp casing with the shaft and engagement of the shaft with the bracket being controlled by the end 9 of the shaft and the lock nut 10, no other fastening means being necessary, and all of these features are possessed by a device that is simple in construction and compact in form and one that is capable of being readily attached to any make of automobile by an unskilled person.

What is claimed is:—

1. A direction signal for vehicles comprising a support carried by one end portion of the vehicle, adjacent the side of the vehicle, a tubular shaft secured to the support, a lamp projecting from one end of the shaft, a lamp casing having a partition therein, said partition cooperating with the rear wall to provide a bearing adapted to receive the shaft, a lens extending over the open end of the casing, each half of the lens being differently colored, and means engaged with the casing for rotating the same upon the shaft to position the desired colored portion of the lens adjacent the side of the vehicle.

2. As an article of manufacture a direction signal of the character described comprising a tubular shaft, a lamp projecting from one end of the shaft, a lamp casing having a pulley channel provided in its outer surface adjacent the rear wall of the casing, a partition disposed within the casing adjacent the rear wall thereof, said partition and rear wall of the casing having registering openings, a sleeve disposed in said openings, said sleeve being adapted to receive the tubular shaft for rotatably supporting the casing, and a variously colored lens carried by the opposite end of the casing, and means disposed within said pulley channel for rotating the casing upon the shaft to alternate the positions of the different colored portions of the lens.

In testimony whereof I hereunto affix my signature.

WILLIAM R. TONKIN.
